TOBACCO FLUE AND HEATING SYSTEM

Charles Irvin Gill, Wilson, N. C., assignor of one-half to A. Roy Moore, Wilson County, N. C.

Application November 14, 1935, Serial No. 49,811

1 Claim. (Cl. 34—19)

This invention relates to a flue and heating system primarily adapted for the coloring, drying, and curing of tobacco, although not so limited, as it may be used for other products, especially those needing processing by dry heat.

It is particularly aimed to provide a system and means wherein practically a uniform temperature may be maintained throughout the curing chamber. In existing systems, the heat cannot be properly controlled and distributed evenly in the curing chamber, and there is an unnecessary use of fuel.

By reason of the present invention, approximately one-third of the fuel used in existing systems may be saved, and it provides a discharge flue for the products of combustion, which flue may have parts in any desired portion of the barn or shed, and within which flue a hot air pipe is disposed, to receive the air adjacent the outlet or vent of the barn, and to discharge the same at intervals through nipples extending through a discharge or primary flue.

The more specific objects and advantages will become apparent from a consideration of the description following taken in connection with the accompanying drawing illustrating an operative embodiment.

In said drawing:—

Figure 1 is a view in perspective of a tobacco barn or shed embodying the present invention, parts of the barn and flue being broken away to disclose details;

Figure 2 is a longitudinal sectional view through a portion of a primary or discharge flue, with a portion of a hot air pipe therein; and

Figure 3 is a cross sectional view taken on the plane of line 3—3 of Figure 1.

Referring specifically to the drawing, wherein like reference characters designate like or similar parts, 10 designates a conventional barn or shed of the type in which tobacco or other products are colored, dried, cured, or processed by dry heat. Said barn has a ventilator at 11.

Within the barn a suitable furnace 12 is provided from which a primary or discharge flue 13 leads, to carry the products of combustion from the furnace 12 to the atmosphere. Such flue 13 has a central longitudinal section 14, leading to branches 15, extending around the ends and sides 50 of the barn and communicating with a vertical portion or stack 16 on the exterior of the barn, preferably T-shaped at its upper end, as at 17.

Within the flue 13 is an air conduit 18 preferably centrally disposed and of less diameter, the air conduit being at the zone to receive the maximum heat from the products of combustion.

Such conduit 18 has a multiplicity of nipples, as at 19, leading therefrom through, and fastened air tight in, the wall of the flue 13, so as to discharge heated air into the interior of the barn or shed 10. It will thus be realized that the products 5 of combustion in the flue 13 cannot enter the air conduit 18 or the interior of the barn or shed 10.

The air for the conduit 18 is taken at the highest point within the barn or shed 10, in order 10 that the heat thereof may be utilized, such air entering through inlet openings or orifices 20 in a horizontal branch 21 of such air pipe, and which communicates with a vertical branch 22, having an L-shaped horizontal branch 23, adjacent the 15 furnace, and entering the conduit 18 a short distance in advance of the furnace. An induction fan device 24, driven by any suitable means, is provided. A damper or valve 25 is provided in the pipe 23 to control or cut off the circulation 20 and flow of air, and the fan 24 obviously is under suitable control to cease operation when desired.

It will be realized that the fan 24 causes air to enter the conduit 18, through the openings 20, the conduit being at the zone of maximum heat 25 with respect to the discharge flue, the air accordingly being heated and substantially evenly distributed throughout the barn or shed, through the nipples 19. As the openings 20 are at the highest point within the barn, some of the 30 escaping air will be taken into the openings 20, and its heat utilized, the air entering the conduit 18 thus in effect being pre-heated.

Various changes may be resorted to provided they fall within the spirit and scope of the invention.

I claim as my invention:—

In a system of the class described, a curing chamber, a furnace in said chamber, a continuous discharge flue portion adjacent the base of said chamber, a flue portion leading from the furnace to the first mentioned flue portion, a discharge stack leading from the first mentioned portion, an air conduit portion within the first and second mentioned flue portions, said chamber having a vent means at the top thereof, an air conduit having an inlet within the chamber adjacent said vent means, said conduit having an induction fan therein, a conduit leading from the last mentioned air conduit to the air conduit in the 45 second mentioned flue portion in front of the furnace, and air discharge nipples leading from the air conduit within the first and second mentioned flue portions and extending through the 50 walls thereof.

CHARLES IRVIN GILL.
